UNITED STATES PATENT OFFICE

JULIUS HEINRICH HOEING, OF COLOGNE-ON-THE-RHINE, GERMANY, ASSIGNOR TO
HANS BILSTEIN, OF ALTENVOERDE, WESTFALEN, GERMANY

HAND STAMPING APPARATUS

Application filed August 13, 1928, Serial No. 299,415, and in Germany April 20, 1928.

My invention relates to a stamping apparatus in which paper, cardboard, leather or other fairly soft material is provided with numbers, letters, ornamentalations etc. by having them impressed therein.

The apparatus exerts, with the aid of the stamp matrix a rapid and high pressure which enables glazed paper, metal foil, bronze paper or coating of other suitable material 10 interposed between the die and the piece to be stamped, to be at the same time pressed into the latter so that this coating holds fast without any special binding means. To this end, the dies are provided with sharp edges 15 which cut the number or the letters of ornamentation out of the coating material and at the same time so press the cut edges into the sharply cut outlines of the number or letter that the coating adheres without further assistance.

The apparatus is characterized by its great simplicity resulting in economy and providing the possibility of working rapidly, obviating repairs, increasing the durably certain working capacity etc.

The essential feature of the apparatus is the co-operation of the stamping mechanism with the die carrier and piece to be stamped in such a manner that by the movement of the 30 stamping mechanism the other parts are automatically brought into the operative position and after completion of the stamping operation automatically return to the position in which the next piece to be stamped 35 is substituted for the stamped piece.

The apparatus is principally suitable for use in places where such stamped goods are directly needed for example in businesses in which the marking of goods as well as their 40 prices constantly change and consequently such notices or display pieces must always be prepared afresh.

A further advantage of the invention may be seen in the fact that the attention required 45 by the apparatus is so simple that unskilled persons can manage it at once.

In the drawings:

Figure 1 is a side view of the apparatus in the position for introducing the type and 50 the pieces to be impressed therewith;

Figure 2 is a plan corresponding to Figure 1;

Figure 3 is a section corresponding to the line A—B of Figure 2;

Figure 4 is a front view of the apparatus 55 as seen from the place in which the piece to be stamped is inserted;

Figure 5 is an under view of the apparatus;

Figure 6 is a section through the die and 60 the piece to be stamped on an enlarged scale, and

Figure 7 shows a further example of the apparatus.

A base plate *a* carries the bearing blocks *b* 65 in which an eccentrically lying roller *d* is rotatably mounted by means of journals *c*. To this roller there is fixed a lever *e* which advantageously consists of a number of parts that can be screwed together and in its position of rest as shown in the drawings lies upon a bracket *f*. Between the bearing blocks there is arranged a stamping bar *g* which is journalled by journals *h* in slots *i* in the bearing blocks and rests on springs *k* which 70 constantly press the stamping bar against the eccentric roller *d*.

Connected with the motive mechanism e. g., the hand lever *e* by means of a ring *l* is a cord *m* which passes over pulley *n* into the 80 recessed portion of the base plate *a* and is connected by a compensating spring *o* with a guide piece *p* which is in turn attached to the base plate by springs *q*. Guide pins *r*, which are movable in slots *s* in the base plate 85 *a*, connect the guide piece *p* with a slide *t* that rests on the base plate *a* and is longitudinally movable thereon and is guided between the bearing blocks *b*.

On moving the lever *e* in the direction of the arrow the cord *m* moves the compensating spring *o* and the guide piece *p*, as well 90 as the slide *t* by means of the guide pins *r*, towards the stamping bar *g*.

The guide pins *r* protrude beyond the slide 95 *t* and carry on springs *z* a frame *w* in the opening *x* of which the die *y* is inserted. The guide pins *r* serve also at the same time with the aid of the springs *z* to keep the frame *w* raised in its position of rest, thus facilitat 100

ing the insertion of the die as well as the substitution of the cardboard or other piece that has been stamped by another. Nuts *u* serve for adjusting the position of the rear portion 5 of the frame *w*, the front portion of which is offset and attached to the slide *t* by a pin *v*.

The operation to the apparatus is as follows:—

- 10 The drawings show the position in which the dies *y* are inserted into the slots *x* and the pieces to be stamped can be placed in the proper position beneath the dies. Since the apparatus is so simple, there will usually be no special guiding frames or the like for introducing the pieces to be stamped; naturally, however, means may be provided as desired, for adjusting the dies in the slot *x* and/or for fixing and adjusting the objects to be stamped on the slide. Generally, however, it 15 will suffice to work by the eye without any special expedient.
- 20 If now the hand lever *e* is turned in the direction of the arrow, the cord *m* pulls the slide *t* together with the frame *w* beneath the stamping bar. Up to that point a concentric circular part of the roller *d* moves on the stamping bar so that the latter is itself not pressed downwardly until the parts to be stamped have arrived entirely beneath the 25 bar. The spring *s* keeps the frame *w* constantly in the raised position, so that on inserting dies *y*, and pieces to be stamped the dies *y* cannot be shifted because they do not come into contact with the pieces to be stamped. When the slide has arrived at its 30 end position so that the dies lie directly beneath the stamping bar *g*, the eccentric pressure begins and enables a rapid and sharp impression by the die to be effected. For this purpose, the hand lever *e* is brought into the 35 position in which it forms the straight continuation of the position shown in the drawings the tension springs *q* can draw the slide *t* back with the aid of the guide piece *p* so that the insertion of the piece to be stamped, the change of the dies, etc., can now be effected.

The dies *y* are so formed that the letters, numbers, or ornamentations are outlined by sharp edges 2. If a glazed paper 3 or the like, as may be seen in Figure 6, is interposed between the cardboard 4, etc., to be stamped and the die *y*, the sharp edges 2 cut the figure out of the paper and press it into the sharp indentations; so that on the stamped part the piece of paper 3 adheres with its glazed surface, since its edges are forced into the stamped edges 6, without the necessity of any adhesive substance or the like for fixing it.

In order that the pieces to be stamped should not be disturbed by the stamping bar *g* on introducing the dies thereunder, the lateral arms 7 of the frame *w* are provided with lugs 8 which depress the frame somewhat on

being moved beneath the stamping bar *g* until the dies *y* lie completely beneath the stamping bar, when the depression of the frame *w* by the lugs 8 can cease. Generally, however, the adjustment of the frame *w* by the nuts *u* is sufficient.

In the example shown in Figure 7 the frame *w* is S-shaped and rests on flat springs 9 arranged on the slide 11. The slide 11 is moved beneath the stamping bar *G*, on rotating the eccentric roller *d* by the hand lever *e* by means of levers 12 fixed to the eccentric journal and by tension cords acting against springs 14 and are moved back by the springs 14 on bringing back the lever *e*.

Since the frame 10 on which the dies rest is curved, it is moved by the stamping bar, on the return of the slide, into the position shown in the drawings in full lines; in this position the dies can be inserted and the pieces to be stamped laid in. On moving the slide 11 towards the stamping bar the curved portion of the frame 10 is freed from the stamping bar and brings the die and the underlying piece to be stamped into contact with each other only when these parts have been brought entirely beneath the stamping bar.

Having thus described and ascertained the nature of my said invention I declare that what I claim is:

1. Manually operable portable embossing apparatus comprising a flat plate forming a base and having bearing blocks, a cylinder eccentrically mounted on the bearing blocks of the said base plate and provided with means whereby the cylinder may be manually turned in its bearings, said cylinder being continuous along its whole length from bearing to bearing and a stamping bar arranged below the cylinder, of a width substantially equal to the diameter of the cylinder and said bar corresponding in length with the cylinder and in direct contact therewith from end to end and springs to maintain said stamping bar in contact with the cylinder from end to end.

2. Manually operable embossing apparatus as claimed in claim 1, including a die carrying element movable to arrange the die under or to one side of the stamping bar, a spring active to normally hold said die carrying element in position to hold the die at one side of the stamping bar and means connected to the cylinder and actuated by the partial rotary movement of the cylinder to move said element to the required position under the stamping bar when said cylinder is actuated to depress said stamping bar.

3. Manually operable embossing apparatus comprising a base, a cylinder eccentrically mounted on the base and provided with means whereby the cylinder may be manually turned in its bearings and a stamping bar arranged below the cylinder and corresponding in length therewith and springs

to maintain said stamping bar in contact with the cylinder from end to end, a die carrying element having a slot extending there-across from end to end to receive an emboss-
5 ing die, said element being movable to ar- range the die under or to one side of the stamping bar, said die carrying element being inclined and provided at its outer end with supporting springs.

10 In testimony whereof I affix my signature.
JULIUS HEINRICH HOEING.
